UNITED STATES PATENT OFFICE.

ADAM L. MOHLER, OF MINNEAPOLIS, MINNESOTA.

UNCOUPLING DEVICE FOR COACH DRAW-BARS.

SPECIFICATION forming part of Letters Patent No. 591,868, dated October 19, 1897.

Application filed April 3, 1897. Serial No. 630,548. (No model.)

To all whom it may concern:

Be it known that I, ADAM L. MOHLER, a citizen of the United States, residing at Minneapolis, in the county of Hennepin and State 5 of Minnesota, have invented certain new and useful Improvements in Uncoupling Devices for Coach Draw-Bars; and I do hereby declare the following to be a full, clear, and exact description of the invention, such as will 10 enable others skilled in the art to which it appertains to make and use the same.

My invention has for its especial object to provide an improved uncoupling device for use on passenger-cars. On this class of cars 15 the Miller—or lateral-action—type of automatic couplers is generally employed. Otherwise stated, the draw-bars are mounted for a limited lateral movement at their outer ends to effect the coupling and uncoupling actions. 20 A stiff spring tends to hold the draw-bars in their coupled position; and the uncoupling has hitherto been effected by a hand-lever on the platform connected by a link or chain directly to the draw-bar. Hence a single stroke 25 of said hand-lever must throw the draw-bar from its coupled to its uncoupled position. From its required location the lever must necessarily be short. From these facts it follows that the available leverage is not large. 30 In practice it often requires two men to operate said lever for the uncoupling action. Uncoupling is especially difficult and sometimes impossible when the cars are standing on curves, because of the excessive friction 35 between the coupled parts.

The object of my invention is to overcome the above-named defects by the provision of an uncoupling device which will afford a large leverage and be convenient and reliable 40 in action.

To these ends my invention consists of the novel devices and combinations of devices hereinafter described, and defined in the claims.

45 The preferred form of my said invention is illustrated in the accompanying drawings, wherein, like characters indicating like parts throughout the several views—

50 Figure 1 is a rear elevation of a passenger-coach equipped with Miller platforms and couplers to which my improved uncoupling devices are attached, some parts of said car

being broken away and the trucks being removed. Fig. 2 is a view, principally in plan, but with some parts broken away, showing 55 one end or platform of the coach illustrated in Fig. 1. Fig. 3 is a perspective view, with some parts broken away and others shown in section, illustrating, on an enlarged scale, the principal details of my improved uncoupling 60 device; and Fig. 4 is a view corresponding to Fig. 1, illustrating the action of the pawl-lever when moved into an extreme position.

1 indicates the body of the coach, which is provided with the ordinary end platforms 2, 65 steps 3, end sills 4, and draft-timbers 5. The couplers shown involve each a draw-bar 6, which terminates at its outer end in a coupler-head 7, to which a pin-locked cam-shaped coupling-beak 8 is pivoted. The inner ends 70 of the draw-bars 6 are secured in the ordinary manner to the draft-timbers 5 by means of a pivot-pin 9.

My improved releasing or uncoupling device will now be described.

a indicates a bracket, the upper flange of which is rigidly secured to the under side of the end sill 4 by means of nutted bolts a'. The lower flange of the bracket a is provided at its outer end with an upturned bearing-lug a², through which and the side web of said bracket a a spindle or pivot-bolt b is passed and rigidly secured, as shown, by means of a nut b'. On this spindle or shaft b a windlass c is loosely mounted. The forward 85 end or hub of the windlass c is left round for a short distance, and is then formed polygonal in cross-section, as shown at c'. A ratchet-wheel d, which is provided with a polygonal central passage, is fitted onto the polygonal 90 portion c' of the windlass c, and is thereby caused to turn with said windlass. A hand-operated pawl-lever f, which, as shown, is bifurcated at its lower end, is pivotally mounted on the projecting cylindrical hub portions 95 of the windlass c, with its prongs straddling the ratchet-wheel d. Just below the crotch formed by the bifurcation of the lower end of the lever f a pawl f' is pivotally mounted on a pin f², which is passed through the 100 prongs of said lever. This pawl f' works over the teeth of the ratchet-wheel d. The pawl-lever f is provided, at its upper end, with a pivoted finger-lever f³, which is con-

nected with the pawl f' by means of a rod f^4 , and is subject to the action of a leaf-spring f^5 , which tends to throw said finger-lever outward and to hold the pawl f' in engagement 5 with the teeth of the ratchet-wheel d .

- The windlass c is connected to the head 7 of the draw-bar 6 by means of a flexible connection, preferably in the form of a chain g . The ratchet-wheel d may be moved in one direction by means of the lever f and pawl f' ; and it will be held from return or unwinding movement by means of the gravity-actuated retaining-pawl k , which is pivoted, as shown at k' , to suitable lugs or projections from the bottom flange of the supporting-bracket a . The free end of the retaining-pawl k lies in the path of the lever-pawl f' , and is somewhat extended and provided with an end notch k^2 , into which the free end of the lever-pawl f' is adapted to engage, when said lever f is given an extreme movement in the direction of its uncoupling throw. By this extreme movement of the lever f the retaining-pawl k may be released or disengaged from 25 the teeth of the ratchet-wheel d , thus freeing the windlass and permitting the chain g to be unwound and the draw-bar 6 returned to its normal position, under the action of the spring 10. As shown, the pawl-lever f works, 30 at its intermediate portion, between parallel guide-irons 11, which are secured together and onto the forward edge of the end sill 4. Said lever f , when out of use, may be held in a vertical position by means of a pivoted or 35 hinged latch-plate p , which is hinged to a companion plate p' , secured on the end sill 4, and is notched or cut out at its free end, as shown at p^2 , to receive and straddle the said lever f .
- 40 The action of my improved uncoupling device is probably obvious from the drawings and the description of the details hereinbefore given. The general operation and advantages of the same, however, may be briefly 45 summarized. The coupling action is, of course, that of the ordinary Miller couplers, which is well understood.

To uncouple the cars or to set the couplers for uncoupling, when the cars shall be drawn 50 apart, my improved uncoupling device is operated as follows: The retaining latch or hinge p is thrown back from the hand-lever f , and the said hand-lever is then operated, with a succession of short throws, for winding 55 the flexible connection or chain g onto the drum or spool c . In these actions of the hand-lever the pawl f' works, of course, on the ratchet-wheel d , and the said ratchet-wheel d , together with the drum c , is held in whatever 60 position it may be set by the retaining-pawl k . By thus introducing a pawl-and-ratchet device, with windlass and chain, and utilizing a series of short throws of the hand-lever, instead of a single long throw, as done with the old hand-lever, it is obvious that a comparatively 65 large leverage is rendered available for pulling over the draw-bar. Hence, one man

can easily operate the said hand-lever and effect the uncoupling under all conditions. When it is desired to release the draw-bar 70 from the uncoupling device, the pawl f' is lifted by gripping the finger-piece f^3 at the head of the hand-lever f , and the hand-lever is then thrown outward to an extreme position, which will have the effect of throwing 75 off the retaining-pawl k and causing the pawl f' of the hand-lever to engage with the notch k^2 of the retaining-pawl, and thus holds the retaining-pawl away from the ratchet-wheel d . As quick as this is done the draw-bar 80 spring 10 will become operative to instantly throw the draw-bar into its coupling position, thereby, of course, unwinding the chain, ready 85 for use when again required in the uncoupling action. The hand-lever f is then brought 90 back to its normal position and locked by the latch or hinge p , which action will permit the gravity retaining pawl k to return to its normal position in engagement with the ratchet-wheel d . 90

From the foregoing description it will be seen that I have provided an uncoupling device of extremely simple construction, which is convenient and reliable, and will enable one member of the crew always to effect the 95 uncoupling action with ease. With this device cars may be uncoupled while a train is in motion; and this is very important, especially when a flying-switch is to be made.

By my improved uncoupling device, therefore, the loss of time to the crews, the delays of the train, and the annoyances to passengers, incidental to the old uncoupling devices, are entirely overcome. The feature of annoyance occasioned by uncoupling cars at night, 100 when the passengers are, of course, usually asleep, has long been noted. Furthermore, the element of accident which is incidental to the operation of the old forms of uncoupling devices is eliminated by my invention. With 105 these old forms of uncoupling devices it is necessary to hold the lever in its uncoupling position until the uncoupling action has been effected; and then, when the lever is released, 110 it will be thrown violently into its normal position under the action of the heavy spring, which returns it, together with the drawbar, as already noted. Obviously, this return movement of the old form of lever is dangerous. As already pointed out in my improved 115 uncoupling device, the coupler may be drawn into its uncoupling position and there held until the cars have been drawn apart; and when the coupler is released by an extreme movement of the lever the said lever is not 120 returned with the said coupler, but is subsequently returned by hand. 125

It will be understood that the details of the construction might be changed without departing from the spirit of my invention. 130

Although especially designed for application to sleepers and coaches equipped with side-action couplers, it will also be understood that my uncoupling device is capable

of application to other forms of couplers, and to railway cars in general, by properly disposing and guiding the flexible connection from the windlass-drum.

5 What I claim, and desire to secure by Letters Patent of the United States, is as follows:

1. The combination with a coupler, of an uncoupling device for the same, involving a ratchet-wheel with intermediate connections to said coupler, a retaining-pawl for holding said ratchet-wheel from return movement, and a pawl-lever coöperating with said ratchet-wheel and operative, by an extreme movement, to disengage said retaining-pawl from 15 said ratchet-wheel, substantially as described.

2. The combination with a coupler, of an uncoupling device for the same, involving a windlass, a ratchet-wheel rotatable with said windlass, a flexible connection from said 20 windlass to said coupler, a retaining-pawl normally holding said ratchet-wheel from return movement, and a pawl-lever coöperating with said ratchet-wheel and operative, by an extreme movement, to disengage said 25 retaining-pawl from said ratchet-wheel, substantially as described.

3. The combination with a coupler, of an uncoupling device for the same, involving a supporting-bracket, a fixed spindle or shaft mounted in said bracket, a windlass loose on 30 said spindle and provided with a projecting hub, a portion of which hub is cylindrical and a portion of which is polygonal in cross-section, a ratchet-wheel mounted on the polygonal portion of said hub, a pawl-lever 35 mounted on the cylindrical portion of said hub and provided with the driving-pawl and releasing device for the same, a gravity-operated retaining-pawl, normally holding said ratchet-wheel against return movement and 40 provided with a projecting portion which extends in the path of said driving-pawl, and a flexible connection between said windlass and the draw-bar of said coupler, substantially as described. 45

In testimony whereof I affix my signature in presence of two witnesses.

ADAM L. MOHLER.
